UNITED STATES PATENT OFFICE.

JOHN A. WEVER, OF BALTIMORE, MARYLAND.

OUTLET-BOX SUPPORT.

1,263,177.

Specification of Letters Patent. Patented Apr. 16, 1918.

Application filed July 3, 1917. Serial No. 178,459.

To all whom it may concern:

Be it known that I, JOHN A. WEVER, a citizen of the United States, residing at Baltimore, in the county of Baltimore and State of Maryland, have invented new and useful Improvements in Outlet-Box Supports, of which the following is a specification.

This invention relates to means for supporting lighting fixtures and is especially designed for use in connection with the installation of electric lighting fixtures in houses already completed.

The primary object of the invention is to provide means for supporting an outlet box to which lighting fixtures of any weight may be secured, without the necessity of removing any part of the flooring of the room above, thereby preventing mutilation or damage of the same, as is usually the case when the said fixtures are supported from the ordinary wooden supporting block.

Another object is to provide means for the insertion of the fixture supporting means between the ceiling and the floor of the room above with the removal of the least possible amount of plaster, the method of inserting the said fixture supporting means permitting of its insertion through the lath spaces and proper positioning thereof for connection with the lighting fixture.

With the above and other objects in view, the invention contemplates the provision of a metal attaching and supporting bar, which is adapted to be positioned so as to light across and bridge a plurality of laths, the bar engaging a sufficient number of laths to enable it to support a fixture of great weight, the manner of positioning the bar and of attaching the outlet box, serving to keep the said bar in proper position without any additional holding means.

The invention further contemplates novel means of placing the bar in position upon the laths and includes the provision of a holding and guiding tool, by means of which the bar may be inserted between the lath spaces and guided to its proper position for engagement with the outlet box, the said bar having attached thereto a flexible element for moving it to the desired position.

In the drawings,

Figure 1 is a perspective view of a fixture supporting bar embodying the present

invention and shown in the act of being inserted through the lath spaces of the ceiling.

Fig. 2 is a sectional view taken through a portion of the ceiling and showing the supporting bar prior to the removal of the holding and guiding tool.

Fig. 3 is a view similar to Fig. 2 with the tool in position for guiding the bar to its proper position, the bar not having yet reached its final adjustment.

Fig. 4 is a detailed perspective view of the bar.

Fig. 5 is a similar view of the holding and guiding tool.

Fig. 6 is a similar view of the outlet box.

Fig. 7 is a detailed sectional view through the outlet box illustrating the manner of engaging the threaded bolt therewith.

Fig. 8 is a sectional view through a portion of the ceiling showing the outlet box connected to the supporting bar.

Fig. 9 is a plan view of a modified form of bar.

Fig. 10 is a detail sectional view on the line 10—10 of Fig. 9.

In the installation of electric fixtures in houses already completed, it is some times customary to project the fixtures through the laths by means of screws fastened through the outlet box. This is a very unsatisfactory method, as it will not support fixtures of any weight.

In order to support heavy fixtures it is customary to secure between the ceiling laths and the floor of the room above a wooden supporting block, but this method necessitates the removal of a portion of the floor, thereby injuring and ruining the appearance of the same.

In order to overcome these and other objects and disadvantages, there is provided the following described invention, which consists of a metal supporting bar 10 of rectangular cross-section, and of a length sufficient to overlie preferably six laths. This supporting bar is adapted to be placed upon and bridge the laths so as to support the weight of the electric lighting fixture, the said fixture being secured to the usual outlet box 11 in the ordinary manner.

The outlet box as stated, is of the usual construction, being provided with a central aperture 12. In the present instance this aperture is closed by means of a plate 13, in which is formed a central screw receiving

opening 14, through which is adapted to pass a screw or bolt 15. This screw 15 has its head engaged upon the end face of the plate 13, the threaded end of the screw being engaged with the opening 16 located intermediate the length of the supporting bar 10, which opening is positioned over one of the spaces between the ceiling laths.

In addition to providing the above described means for supporting a fixture, the invention contemplates a novel means for positioning the said supporting means within the ceiling without in any way mutilating the plaster or laths, so that the fixture may be positioned without damage to the appearance of the room.

With this end in view, there is provided a holding and guiding tool 17, one end of which is approximately at right angles as shown at 18 and is formed with a reduced V-shaped extremity 19. This extremity 19 is provided for engagement with a V-shaped slot 20 formed in one end of the supporting bar 10, the said slot extending transversely through the bar, but terminating short of the opposite edge thereof. The opposite end of the tool 17 is enlarged as shown at 21 and is provided with an opening 22, through which the bar 10 may be guided, when the tool is in proper position, the enlarged end 21 of the tool being formed with a slot 23 to provide an entrance into the opening 22, this slot being of a sufficient width to permit the passage of the bar 10 therethrough.

This method of holding the supporting bar by means of the guiding tool 17 provides a positive connection between the bar and tool, the weight of the bar preventing any accidental disengagement between these two sections, by providing a binding connection therebetween. As soon as the bar rests upon the laths or ceiling, however, this weight is released and the tool 17 may be readily disengaged from the V-shaped slot in the end of the bar.

The supporting bar is further provided with a relatively small aperture 24, preferably located adjacent the threaded opening 16, the aperture 24 being provided with an attachment of a flexible element 25, in the form of a fine wire or string.

In positioning the bar, a small portion of the plaster 26 of the ceiling is cut away to provide an opening 27, and the tool is engaged with the slot 20 and inserted vertically through the opening and between the laths as shown in Fig. 1 of the drawings, the flexible elements 25 being attached thereto. After passing through the space between the laths, the bar 10 is laid horizontally across the same as shown in Fig. 2 of the drawings, the tool 17 being moved laterally of the bar and longitudinally of the laths for a slight distance to disengage the

same from the slot 20. The tool is then reversed, the larger end 21 thereof being inserted between the laths, with the flexible element 25 threaded through the opening 22. This element 25 is pulled so as to bring the end of the bars 10 to the space between the laths through which the tool is inserted, the end of the bar entering the opening 22 of the tool, through which it is guided and moved until the opening 16 is directly above the space between the laths, through which the tool has been inserted. The tool may then be disengaged from the bar by moving said tool laterally so that the passage 23 of the tool passes across the bar, the tool then being withdrawn through the lath space. The outlet box is then secured to the bar 10 in the manner previously described.

The flexible element 25, which is attached to the bar, is not only useful for positioning the bar in a manner to permit connecting of the outlet box, but also provides a means for holding the bar in position while engaging the bolt carried by the outlet box. This use of the flexible element 25 is important, because without some means for holding the bar it would be a difficult task to engage the bolt, especially when there are a number of wires at the outlet to contend with.

When the device is used to support the standard type of outlet box for wires, all of the knockout holes for the passage of the said wires into the box are left unobstructed, with the exception of two, over which the supporting bar lies when properly positioned within the ceiling.

In the modification shown in Figs. 9 and 10 of the drawings, the bar 10^a is preferably enlarged as shown at 10^b at a point approximately central of its length, and is provided with a preferably rectangular opening 30, in which there is pivotally mounted a nut 31, the threaded opening 32 of this nut being adapted to receive the end of the screw 15 of the outlet box. The nut 31 is pivoted within the opening 30 by means of oppositely extending pins 33, carried by the bar 10^a and engaging sockets of each side of the nut 31. This construction provides for arranging the supporting bar at an angle for the accommodation of furring strips, the mounting of the nut permitting of the proper positioning of the lighting fixtures.

It will thus be seen that the invention provides means for supporting an outlet box of any standard type, either with or without a fixture stand. By the use of the invention, the operation of installation and positioning the outlet box on either a metal lath or wood lath ceiling, in a finished house, can be accomplished with a fraction of the labor and time, that would be involved in doing the same thing by the usual methods. Also the resulting work will be more secure.

It is believed that from the foregoing de-

scription when taken in connection with the accompanying drawings, the construction, operation and advantages of the invention will be apparent. The right is reserved to 5 make such changes in the form and proportion of the invention as will fall within the scope of the appended claims.

Having described the invention, what is claimed is:

- 10 1. An outlet box support and means for positioning the same, including a metal supporting bar positioned transversely upon the ceiling laths, means for connecting the lighting fixture to said bar and means engageable with said bar for inserting and positioning the bar.
- 20 2. An outlet box support and means for positioning the same, including a metal supporting bar positioned transversely upon the ceiling laths, means for connecting the lighting fixture to said bar and means engageable with one end of said bar for inserting and positioning the bar.
- 25 3. An outlet box support and means for positioning the same, including a metal supporting bar positioned transversely upon the ceiling laths, means for connecting the lighting fixture to said bar and a combined holding and guiding tool for inserting and positioning the bar.
- 30 4. An outlet box support and means for positioning the same, including a metal sup-

porting bar positioned transversely upon the ceiling laths, means for connecting the lighting fixture to said bar, a combined holding and guiding tool, said tool having at one end a bar engaging extremity disposed at right angles to the body of the tool and its opposite end a bar receiving loop.

5. An outlet box support and means for 40 positioning the same including a metal supporting bar positioned transversely upon the ceiling laths, means for connecting the lighting fixtures to said bar and means laterally engageable with said bar for inserting and 45 positioning the latter.

6. An outlet box support and means for positioning the same including a metal supporting bar positioned transversely upon the ceiling laths, means for connecting the lighting fixture to said bar, means for inserting and guiding the bar within an opening and a flexible element connected to the bar for positioning the latter within the opening.

7. An outlet box support and means for 55 positioning the same, including a metal supporting bar positioned transversely upon the ceiling laths and having a transversely disposed slot therein, means for connecting the lighting fixture to said bar and means engageable with the transversely disposed slot 60 for inserting the bar within and opening.

In testimony whereof I affix my signature.
JOHN A. WEVER:
